UNITED STATES PATENT OFFICE.

THOMAS H. SEELY, OF MALDEN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LEVELING-MACHINE.

1,280,875.

Specification of Letters Patent.

Patented Oct. 8, 1918.

Application filed August 2, 1917. Serial No. 184,043.

To all whom it may concern:

Be it known that I, THOMAS H. SEELY, a citizen of the United States, residing at Malden, in the county of Middlesex and State 5 of Massachusetts, have invented certain new and useful Improvements in Leveling-Machines; and I do hereby declare the following to be a full, clear, and exact description of the invention, such as will enable others 10 skilled in the art to which it appertains to make and use the same.

The present invention relates to improvements in machines for leveling boot and shoe soles, and more particularly to machines of this type which exert a direct leveling 15 pressure upon the shoe sole.

The object of the present invention is to improve the construction, organization and mode of operation of direct pressure leveling 20 machines to improve the efficiency of the leveling operation.

With this object in view, a feature of the invention contemplates the provision in a machine of this type having a pair of jacks 25 and coöperating forms, of a single cam and operative connections between the cam and each jack for alternately moving the jacks from a vertical position of presentation into an inclined position of pressure, and means 30 for stopping the cam with one of the jacks located in a position of pressure.

Still further features of the invention consist in certain novel features of construction, combinations and arrangements of parts 35 hereinafter described and claimed, the advantages of which will be obvious to those skilled in the art from the following description.

The preferred form of the invention is 40 shown in the accompanying drawings, in which Figure 1 is a front elevation of a direct pressure, sole leveling machine embodying the features of the present invention; Fig. 2 is a side elevation of the machine 45 shown in Fig. 1; Fig. 3 is a detail of the brake mechanism; and Fig. 4 is a detail showing a sectional elevation of one of the form supports.

The sole leveling machine shown in the 50 illustrated embodiment of the invention is provided with duplicate jacks and coöperating forms to permit the leveling of one shoe sole during the removal of a finished

shoe and the application of a new shoe. To this end the machine comprises two jacks 55 10, coöperating with forms 12 to level the shoe soles by direct pressure. The operating mechanism immediately connected with each jack and form is duplicated, and accordingly a specific description of the mechanism for operating one jack and coöperating form will be sufficient for a complete understanding of the entire machine.

The jack 10 is removably mounted upon a supporting bed 14, and is held thereon in the usual manner by a sliding pin 16. The bed 14 is provided with a pair of downwardly projecting arms 18 having holes in their lower ends, in which is fixed a stud 20 which is loosely received in the upper end of a link 22 pivoted on a stud 24 fixed in the upper end of a jack actuating lever 26. The link 22 is provided with an upwardly extending split portion 28, the upper end of which is grooved to receive a collar 30 75 of an adjusting screw 32, the rear end of which is threaded in a boss 34 depending from the jack, and the forward end of which is loosely received in a second boss 36. This construction is such that when the screw 32 80 is turned, it being held from longitudinal movement by the engagement of the collar 30 with the vertical slot in the part 28 of the link 22, the jack is moved through an arc of which the stud 20 is the axis, to adjust 85 the jack with relation to the coöperating form. When the jack has been adjusted in correct position relatively to its coöperating form, the split end 28 of the link 22 is tightened upon the collar 30 by means of a screw 90 38, thereby clamping the jack 10 in a fixed position relative to the link 22. The jack is guided from the shoe-receiving position, that is, its position of presentation, as shown at the left of Fig. 2, into the sole leveling position, that is, its position of pressure, by means of a guide cam 40 secured at its front end, by means of a bolt 42, to a boss projecting upwardly from the front part of the frame 44 of the machine. The guide cam is 95 secured at its rear end by a bolt 46 to a boss on the machine frame. The cam guide is provided with a cam groove 48, the forward end of which is in the form of a horizontal arc, and the rear end of which is obliquely 100 positioned and in alinement with the form 12.

The cam groove 48 is engaged by a cam roll 50 fulcrumed on a stud projecting laterally from the jack table 14. By means of this construction, when an upward pressure is exerted upon the stud 24, upon which the link 22 is fulcrumed, it being borne in mind that the jack is in fixed relation to the link 22, the jack is forced to describe an arc which moves the jack into alignment with its coöperating form, and then further upward pressure on the stud 24 causes the jack with the shoe thereon to be forced against the coöperating form.

The form 12 is secured to a form-holder 54, which is secured to a crosshead 56 so as to be capable of lateral adjustment relative thereto. A latch 59 pivoted on the forward end of the form-holder and arranged so that its free end drops down over the forward end of the form, holds the latter in operative position. The outer ends of the crosshead 56 are slidably supported upon guide rods 58, secured at their lower and upper ends in bosses on the machine frame. It will be observed that the guide rods 58 slope backwardly from the front of the machine at an angle of about 45°. As a result of this construction, when one jack is in a position of pressure and the other jack is in a position of presentation, the operator is permitted considerable freedom of movement and may conveniently remove the leveled shoe and place an unleveled shoe in the machine without having his movements interfered with by the operating parts of the machine.

The crosshead 56 is provided with a centrally disposed bolt 60, on the upper end of which is rotatably mounted a hand-wheel 62 provided with an externally threaded sleeve 64 which is in threaded engagement with a cross-piece 66 extending across the upper end of the machine frame. Between the lower end of the sleeve 64 and the upper end of the crosshead 56 is interposed a heavy spring 68. For the purpose of adjusting the tension of the spring 68, the upper end of the bolt 60 is threaded to receive a split nut 70. To adjust the tension of the spring 68 the hand-wheel 62 is held and the nut 70 is turned on the screw 60. To adjust the vertical position of the form relatively to its coöperating jack, the hand-wheel 62 is turned. This movement of the hand-wheel shifts the form and its associated parts without affecting the tension of the spring 68.

The jack is actuated to move from its position of presentation into its position of pressure in engagement with the coöperating form by means of the jack actuating lever 26, which is pivoted on a stud 72 secured in the machine frame. The lower end of the jack actuating lever 26 carries a cam roll 74 which is adapted to engage the cam surface 75 of a jack actuating cam 76 formed

on the side of a large gear wheel 78 journaled on a longitudinally disposed shaft 79. It will be observed, by referring to Fig. 1, that the cam 76 is concentric with the gear wheel 78, and by referring to Fig. 2 that its cam surface is obliquely disposed, being in the form of an ellipse and having a high point and low point diametrically opposed. This jack actuating cam 76 is adapted to actuate both jacks, and the construction and arrangement of parts are such that the cam roll 74 connected with one jack is in engagement with the high point on the cam surface 75 while the cam roll connected with the other jack is in engagement with the low point on the cam surface 75. The jacks will consequently be actuated alternately, and the first jack will be in a position of pressure when the other jack is in a position of presentation, which are the positions shown in the drawings. It is thus seen that one-half a revolution of the gear-wheel 78 serves to move the jack from a position of presentation to a position of pressure, and vice versa.

The gear-wheel 78 is actuated by a pinion 80 carried on the forward end of the main shaft 82 journaled in the middle part of the machine frame. On the rear end of the main shaft 82 is fixed one member 84 of a cone clutch, and just forward of the member 84 is loosely mounted on the main shaft a belt-driven pulley 86 constituting the second member of the clutch. When it is desired to throw the machine into operation, the pulley 86 is moved longitudinally on the shaft 82 into engagement with the clutch member 84 by means of a sleeve 88 slidably mounted on the shaft just forward of the pulley 86. The sleeve 88 is grooved to receive pins projecting inwardly from a yoke 90 carried on the upper end of a clutch lever 92 pivoted at 94 on the machine frame. The lower end of the clutch lever 92 is connected by means of an adjustable link 96 with the upper end of a lever 98 pivoted at 100. The lever 98 has a horizontally disposed arm 102 which is adapted to be engaged by a setscrew 104 threaded in a lateral projection 106 of the treadle 108, which is also pivoted at 100. When the forward end of the treadle 108 is depressed, the setscrew 104 is brought against the arm 102 of the lever 98, which acts, through the link 96, to move the upper end of the lever 92 rearwardly, thereby forcing the loose and rotating pulley 86 into engagement with the clutch member 84, to cause the gear-wheel 78 to rotate. By means of the adjustable link 96 the driving engagement between the pulley 86 and the clutch member 84 is regulated. A spring 110 connected at its lower end with the treadle 108 and at its upper end with the machine frame, serves to maintain the treadle normally in raised position so that

the setscrew exerts no pressure on the arm 102. A spring 111 is thereupon free to disengage the sleeve 88 from the hub of the pulley 86.

5 Inasmuch as it requires only a one-half revolution of the gear-wheel 78 to move the jacks from a position of presentation to a position of pressure and vice versa, it is necessary to stop the machine when one cam 10 roll 74 travels from the lowest point on the cam surface 75 to the highest point, and when the other cam roll 74 travels from the highest point to the lowest. For this purpose a treadle control or stop mechanism is 15 provided, comprising a lever 112 pivoted on the machine frame. The lever 112 is connected by means of a link 114 with another lever 116 pivoted on the machine frame. The free end of the lever 116 carries a cam 20 roll 118, which is arranged to engage the peripheral cam surface 120 of an annular cam 122 arranged concentric with the cam 76. The cam surface 120 is provided with two high points and two low points, so that 25 it completes its function in one-half a revolution. A spring 124 forces the cam roll 118 into engagement with the cam surface 120. When the treadle 108, which is guided in its up and down movements between guides 126, 30 is depressed so as to start the gear-wheel 78 and its connected cams 76 and 122 into rotation, this rotation being in the direction of the arrow (Fig. 1), the high point of the cam surface 120, with which the cam roll 118 35 was at this time in engagement, passes beyond the cam roll 118, and the spring 124 acts to force the cam roll against the corresponding low point of the cam surface 120. This movement of the lever 116 acts to swing 40 the vertically disposed arm of the lever 112 over the boss 132 on the upper side of the treadle 108, thereby holding the treadle depressed and the machine in operation while the gear-wheel and its connected cams 45 complete a one-half revolution. As the cam 122 rotates, the cam roll 118 is forced outwardly by the other high point on the cam surface 120, thereby disengaging the vertically disposed arm of the lever 112 from the 50 boss 132 on the treadle 108, and thereby permitting the treadle to be raised and the machine stopped.

In order to stop the machine when the highest point on the cam surface 75 reaches 55 the cam roll 74, so as to insure the greatest pressure on the shoe sole while the jack is in a position of pressure, a brake device is provided comprising a brake disk 134 secured to the main shaft 82. The rim of the brake 60 disk 134 is in the form of a lateral flange 135, the inside circumference of which is adapted to be engaged by two semi-circular brake members 136 and 138 pivoted on one end of an arm 142 of a brake support 144 fulcrumed on the main shaft 82. On the outer 65 end of an arm 146 of the support 144 is fulcrumed a brake actuator 148, which is in the form of a pin, the brake actuating end of which is elliptical and is received between the free ends of the brake members 136 and 138, and the other end of which is pinned to an arm 150. When the arm 150 is depressed, the brake actuator 148 is turned to present its least diameter to the free ends of the brake members. When the actuator is in 70 this position, the brake disk 134 rotates freely about the brake members, but when the arm 150 is raised so that the major axis of the ellipse is presented to the free ends of the brake members, they are caused to 75 move radially outward and tightly engage the flange 135 of the brake disk 134. Thereupon as the disk continues to attempt to rotate, a stop arm 152 depending from the hub of the support 144, is brought into engagement with a stop 154 fixed on the machine frame. A screw 156 regulates, within certain limits, the distance through which the stop arm 152 moves after the brake members 80 136 and 138 come into braking engagement 85 with the brake disk. The narrow space separating the end of the screw 156 from the stop 154 and through which the brake device as a whole moves when the brake is thrown into operation, is provided for the purpose 90 of allowing the machine to stop without a sudden jar. The arm 150 is connected by means of an adjustable link 158 with the treadle 108. Inasmuch as the brake mechanism and the clutch mechanism are both operated through the treadle 108, the connections between the treadle and the lever 98 are such as to permit each mechanism to be 95 separately and independently adjusted. Moreover, when the treadle is released so 100 that the spring 110 acts to move the link 158 upwardly to throw the brake mechanism into operation to stop the machine suddenly and without jar, the spring is relieved of the weight of the connections between the lever 105 98 and the sleeve 88, and therefore the braking operation is performed more efficiently. 110

When the leveling operation is completed and the jack is about to descend from its position of pressure to its position of presentation, a cam surface 160 on the cam 122, the hub of which is in rabbeted connection with the hub of the gear-wheel 78, acts upon an extension of the pin 162 upon which the roll 74 is fulcrumed. The action of the cam 160 115 120 against the pin 162 starts the jack out of its position of pressure, and thereafter the weight of the parts connected with the jack is sufficient to return it into the position of presentation.

125 While it is preferred to employ the specific construction and arrangement of parts shown and described, it will be understood that this construction and arrangement is not essential except so far as specified in the 130

claims, and may be changed or modified without departing from the broader features of the invention.

The invention having been described, what is claimed is:—

6. 1. A sole leveling machine having, in combination, a pair of jacks and coöperating forms, an actuating lever having a fixed fulcrum and supporting each jack at one end, 10 a single cam operatively connected with the opposite ends of both levers for moving the jacks alternately from a vertical position of presentation into an inclined position of pressure, and means for rotating the cam.
15. 2. A sole leveling machine having, in combination, a jack, a coöperating form, an actuating lever supporting the jack, means for adjusting the jack angularly with respect to the actuating lever, means for operating the lever to move the jack from a position of presentation to a position of pressure and vice versa, and means for guiding the movements of the jack to cause the latter to assume a vertical position of presentation and an inclined position of pressure.
20. 3. A sole leveling machine having, in combination, a pair of jacks and coöperating forms, an actuating lever having a fixed fulcrum and supporting each jack at one end, 30 a single cam operatively connected with the opposite ends of both levers for moving the jacks alternately from a vertical position of presentation into an inclined position of pressure, and a stationary guide for controlling the movements of each jack.
35. 4. A sole leveling machine having, in combination, a jack, a coöperating form, means for supporting the jack comprising a jack actuating lever, a link pivoted thereto and having the jack fulcrumed upon the free end, means for normally preventing the jack from turning on its fulcrum, and means for adjusting the jack about its fulcrum.
40. 5. A sole leveling machine having, in combination, a jack, a coöperating form, means for actuating the jack to move it into a position of pressure with respect to the form, and means for initiating its movement from a position of pressure to a position of presentation, said jack and its actuating means

being constructed and arranged to permit the jack to complete the last-named movement by gravity.

6. A sole leveling machine having, in combination, a jack, a form, means for actuating the jack to bring it into a position of pressure with respect to the form, comprising a lever, a cam, and cam driving means, and a second cam for temporarily engaging the lever to force the jack out of a position of pressure.

7. A sole leveling machine comprising a lever pivoted to move about a fixed fulcrum, a rotary cam operatively connected with the lower end of the lever, a shoe supporting jack, a link connecting the jack with the upper end of the lever, and means for guiding the movements of the jack.

8. A sole leveling machine having, in combination, a pair of stationary forms, a pair of shoe supporting jacks coöperating with the forms, a rotary face cam, and a pair of actuating levers pivoted for rocking movement about fixed fulcrums, each supporting a jack upon its upper end and having the lower ends arranged in operative relation to opposite sides of the face cam to cause the jacks to be alternately moved by the cam from a position of presentation into a position of pressure.

9. A sole leveling machine having, in combination, a jack, a coöperating form, means for supporting the jack comprising a lever, a link pivoted on the lever for supporting the jack, means for normally holding the jack in fixed angular relation with the link, means for adjusting the jack with respect to the link, and means for actuating the jack.

10. A sole leveling machine having, in combination, a jack, a coöperating form, 90 actuating means for the jack comprising a lever fulcrumed in the machine frame, a cam mounted on a horizontal shaft for moving the lever, pivotal connections between the lever and the jack, and a guide for guiding the jack, the whole being constructed and arranged to hold the jack in a vertical position of presentation and in an inclined position of pressure.

THOMAS H. SEELY.
